UNITED STATES PATENT OFFICE.

WILLIAM ALBERT COLLVER, OF MARSHFIELD, OREGON.

HEATING SYSTEM.

Original application filed April 21, 1922, Serial No. 555,861. Divided and this application filed June 6, 1923. Serial No. 643,758.

To all whom it may concern:

Be it known that I, WILLIAM ALBERT COLLVER, a citizen of the United States of America, and a resident of Marshfield, in the 5 county of Coos and State of Oregon, have invented a new and Improved Heating System, of which the following is a description.

My invention relates to a heater associated with a fireplace.

10 The present application is a division of an application filed by me April 21, 1922, Serial No. 555,861.

15 The general object of the invention is to provide air heating means to conduct air into and downwardly through the chimney having novel valve means controlling the air flow.

20 Reference is to be had to the accompanying drawings forming a part of this specification, it being understood that the drawings are merely illustrative of one example of the invention.

Figure 1 is a front elevation of a fireplace and its casing embodying my invention;

25 Figure 2 is a partly sectional front view;

Figure 3 is a transverse vertical section; Figure 4 is an enlarged horizontal section on the line 4—4, Figure 3;

30 Figure 5 is a perspective view with parts broken out showing the smoke stack and chimney assemblage;

Figures 6 and 7 are horizontal sections respectively on the line 6—6 and 7—7, Figure 2;

35 In carrying out my invention in accordance with the illustrated example, the fireplace 10 of any suitable form has a grate 11 made of pipe sections and connecting with a water back as hereinafter referred to. A

40 heater coil 12 with a covering plate 13 constitutes a door for the front of the fireplace, said door sliding in vertical guide slots 14 in the casing 15. The numeral 16 indicates hanger chains secured at their upper ends

45 as by bolts 18 to any fixed part 19 of the chimney place or frame structure. Said hanger chains are suitably connected with the bolts 18 and as here shown they are connected through the medium of hanger rods

50 17 although they may be connected direct with said bolts 18. At the lower ends the hanger chains are secured to a pipe member appurtenant to the coil 12 at the top and secured by clasps around each pipe of coils 20.

The hanger chains 16 are for the purpose of 55 allowing the coils 20 to spring in each portion thereof sufficient for the door to drop to the bottom of the fireplace front.

The lower end of one coil 20 extends downwardly as at 21 to a connection at the bottom of the coil 12 while the other side coil 20 connects with the top of said coil 12. The upper ends of the coils 20 connect respectively with range boilers 23 which advantageously have associated therewith a steam escape valve 23a.

For holding the door in the lowered position a horizontal locking shaft 24 is provided having a handle 25 and formed with cams 26 that bear against locking levers 27 70 fulcrumed between their ends as at 27a and having studs 28 projecting laterally outward and adapted to have guiding movements in vertical side slots 29 (Figure 3).

Rigid with the coil 12 at the top is a 75 frame-like bar 30 to which connects the lower ends of flexible cables 31 that extend upwardly and over sheaves 32 and then downwardly to a connection with the trunnions 33 of one of the hoop or ring scrapers 80 35 disposed within a stack 36, said scrapers being connected by a vertical bar 34. One of the scrapers 35 below the trunnions 33 carries a damper 37 provided in the stack 36.

The damper 37 has a weight 39 at one side 85 of the trunnions 33 and at the opposite side there is secured to the damper links 38 to which a chain 40 is secured, said chain having a spring 40a interposed therein, the chain extending downwardly to a connection with a crank arm 41 on a rear door 42 trunnioned between its ends as at 43 at an oblique opening at the back of the stack 36 at the base of the latter directly above the fireplace 10. The stack communicates with the fireplace 10 at the top through an opening 44. When the door coil 12 is raised in the slots 14 the scrapers 35 are lowered, thereby slackening the chain 40 and permitting the damper 37 to open. Damper 37 closes with the lowering of the door coil.

At the bottom of the fireplace 10 is a door 53 trunnioned between its ends as at 54 and leading to an ash-box 55 in the pit 56 below the fireplace. A second lift door 57 is provided for the pit 56 at the back of the fireplace 10.

The grate 11 has a water back 58 connected

by pipes 59 with the boilers 23, the numeral 60 indicating the cold water inlet pipes of said boilers.

A by-pass heater pipe 61 is provided, extending transversely through the ash pit and rising at opposite sides of the grate, the upper ends of said pipe extending laterally inward to a connection at its opposite ends with the stack 36, one of said ends disposed above the other, the damper 37 being disposed between the two pipe ends so as to force smoke through that end of the pipe 61 below the damper to cause the smoke to circulate through said pipe 61 and to return to said stack 36 above said damper 37. Thus, said pipe 61 aids in heating the air in casting 15.

I provide in the chimney structure 63 surrounding the top of the smoke stack 36 air inlet boxes 62 having hinged inner sides or valves 64 to pass air inwardly through the chimney 63 to interior air passages 65, in which the air rises and passes over vertical baffle plates 66 and downward through air ducts 67 one side 68 of each of which rises to near the top of the chimney. In Figure 5 the top layers of the chimney are omitted in the interest of clearness as will be noted by comparing Figures 3 and 5. The air ducts 67 lead downwardly through a double wall bushing 69 set in the fixed structure 19 at the base of the chimney, the air passing from between the double walls laterally at opposite sides of the stack 36 into air pipes 70 which extend downwardly in the casing 15, the outer lower ends terminating in lateral bends, the outlet of each of which is controlled by a valve 71. The stem 72 of the valve 71 has a cross arm 73 rockably mounted on the pipe 70 as at 73^a (Figure 6) and terminates in weighted arms 74 balancing the valve so that it will hang sensitive to changes of air pressure within the casing 15. Above the fireplace at each side the casing 15 has slatted ventilators 75, a rod 76 connecting the slats, extending below the same for convenient operation. Said rod may have a knob 77 thereon slightly above the lower end. When the slats are opened the rod 76 may be set into a cup 78 on the front of the casing 15 to prevent downward movement of said rod and thereby hold the slats open.

On top of the chimney is a fixed plate 80 through which the smoke stack 36 has its outlet and above the plate 80 and spaced therefrom is a cap 81 affording an air inlet and serving as a protector for the smoke stack. Said cap is suitably supported as by standards 81^a. Within the cap 81 at the lower edge is a valve plate 82 above and parallel with the plate 80. Said plate 82 is hung as by links 83 on one arm of each of a plurality of levers 84 which lever

is hung between its ends as at 85 on the under side of the cap 81. The other arm of each lever 84 is secured to a balancing weight 86.

With the above described construction 70 when the door coil 12 is lowered the water therein will be heated and rise, the water circulating through the connection with the range boilers 23. When said door 12 is raised the scraper rings 35 will lower in the stack 36 through the described connection with the cables 31 and in the raised position of the door and the lowered position of the valve 37, the slack in the chain 40 will permit of the damper to swing open thus allowing free passage of smoke. The lowering of the door will raise the scrapers 35 and the valve 37 disposing the latter between the opposite ends of the by-pass 61 and thereby causing the smoke to circulate through said by-pass 61. The opening of the back door 42 will also open damper by slackening chain at its lower end thus allowing free passage of smoke while trash is fed into fireplace. The back door 42 should never be opened unless the front door is closed.

The inlet of air through the valve 64 and the passage of the air as described through the pipe 70 will continue whenever the valves 71 are open. When the heat in the case 15 is highest the pressure of the heated air will close the valves 71. When, however, the ventilators 75 are opened and the heated air allowed to escape into the room, the air pressure in the case will lower and the weights 74 will open the valve 71 permitting the passage of air from the inlet 62 through the described air passages and ducts surrounding the chimney 63 to and through the pipes 70 to the casing 15. The valve assemblage at the top of the chimney 63 will function according to the draft through the stack 36, a strong draft serving to overcome the lowering tendency of the weight 86 and the weight descending as the draft reduces, thereby raising the opposite ends of the levers 84 to raise the valve plate 82.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A fireplace heater including a fireplace, a smokestack, a chimney surrounding the smokestack at the upper end and having valved air inlets, air ducts disposed between the chimney and smokestack and leading upwardly from the inlets and then down-

wardly, a casing about the fireplace, air pipes in said casing at opposite sides of the fireplace, and communicating with the air ducts to receive air therefrom, and balanced valves controlling the outlet of air from said pipes to the interior of the casing and subject to variations of pressure therein.

2. A fireplace heater including a fireplace, 10 a smokestack, a chimney surrounding the smokestack at the upper end and having valved air inlets, air ducts disposed between

the chimney and smokestack and leading upwardly from the inlets and then downwardly, a casing about the fireplace, air 15 pipes in said casing at opposite sides of the fireplace, and communicating with the air ducts to receive air therefrom, and balanced valves controlling the outlet of air from said pipes to the interior of the casing; together with ventilators in the casing to permit escape of air therefrom for varying the pressure on said valves.

WILLIAM ALBERT COLLVER.
